UNITED STATES PATENT OFFICE.

MARK A. WATERHOUSE, OF BOSTON, MASSACHUSETTS, ASSIGNOR TO AI
WATERHOUSE, OF DURHAM, MAINE.

CORSET.

SPECIFICATION forming part of Letters Patent No. 339,719, dated April 13, 1886.

Application filed November 20, 1885. Serial No. 183,399. (No model.)

To all whom it may concern:

Be it known that I, MARK A. WATERHOUSE, of Boston, in the county of Suffolk, State of Massachusetts, have invented a certain new and useful Improvement in Corsets, of which the following is a description sufficiently full, clear, and exact to enable any person skilled in the art or science to which said invention appertains to make and use the same, reference 5 being had to the accompanying drawings, forming part of this specification, in which—

Figure 1 is an isometrical perspective view of my improved corset with the bustle in its normal position; Fig. 2, a like view, the bustle 15 being represented as extended; Fig. 3, an enlarged perspective view of one of the springs of the bustle detached; Fig. 4, a vertical longitudinal section showing the bustle extended, and Fig. 5 a perspective view showing a modification of my improvement.

Like letters of reference indicate corresponding parts in the different figures of the drawings.

My invention relates to that class of corsets 25 which are provided with bustles; and it consists in a novel construction and arrangement of the parts, as hereinafter more fully set forth and claimed, by which a more effective and desirable article of this character is produced 30 than is now in ordinary use.

In Letters Patent of the United States No. 290,505, dated December 18, 1883, and No. 321,408, dated June 30, 1885, corsets are 35 respectively shown having bustle attachments which are similar in some respects to that represented in Figs. 1 and 2, my present invention being designed as an improvement on the corsets shown in said Letters Patent.

In the drawings, A represents the body of 40 the corset, and B the bustle. The body opens both at the back and front, and is provided with eyelets *h*, lacings *f*, and clasps *J*, in the usual manner. The bustle is formed in two sections, the adjoining edges of the sections 45 being provided with eyelets *i* and laced together by the cord *m*.

A series of vertically-arranged elongated sheaths, *k*, are formed in the body of the corset at either side of the opening in the back, 50 said sheaths being preferably long enough to

extend downwardly to the waist or smallest part of the body, and having their lower ends open. They may, however, be made slightly longer, as shown in Fig. 2, or slightly shorter, as shown in Fig. 5, if desired.

The bustle consists of a body composed of 55 jean or any other suitable material, each of its sections being provided with one or more elastic metallic springs, *E*, which are curved or bent outwardly near their centers, as shown at *z*, and downwardly, as shown at *d*, the upper portions or bodies, *r*, being adapted to enter the sheaths *k* on the body of the corset.

The body of the corset is provided with a series of eyelets, *t*, at either side of the lace- 65 opening in its back and below the sheaths *k*, a corresponding series of eyelets, *l*, being inserted in the upper portion of each of the sections *C D* of the bustle *B*. A lacing string or cord, *v*, is inserted in the eyelets *l*, said cord 70 also passing through the eyelets *t* in the body *A*.

In the use of my improvement the body *A* is put on by the wearer and secured by the clasp *J*, being previously laced down the back, in the usual manner, by the lacing or cord *f*. 75 The sections *C D* of the bustle *D* are then laced together by the cord *m*, after which the upper portions, *r*, of the springs *E* are inserted in the sheaths *k* on the body *A*, and when properly adjusted the bustle is secured to said body 80 by the attaching-cord *v*.

The principal objects of my present invention are to render the bustle readily detachable from the body of the corset and readily adjustable vertically thereon, both of which 85 are accomplished in a manner which will be understood by all conversant with such matters without a more explicit description.

By dividing the bustle into two sections, *C* *D*, as shown in Figs. 1 and 2, it may be adjusted laterally as well as vertically, and by unfastening the clasp *J* the corset may be taken off in the usual manner without detaching the bustle from the body *A*. I do not, however, confine myself to making the bustle 95 in two sections, or to lacing the body of the corset at the back, as shown in Figs. 1 and 2, as the body of the bustle may be formed in one piece, or its sections *C D* made integral, and the body *A* of the corset be laced at the 100

sides, instead of the back, if preferred, as shown in Fig. 5; neither do I confine myself to the use of a cord and eyelets for securing the bustle in position on the body of the corset, as any other suitable means for that purpose may be employed, if desired, and instead of the lacing-cords *f m v*, any other suitable means of securing the parts to which they pertain may be used.

10 In the corsets shown in the drawings the bustles are represented as provided with four springs each; but it will be obvious that two or more may be used, if desired, or in accordance with the size and style of the corset. The lower ends, *d*, of the springs are preferably separated to a greater extent than the central portions, *z*, or are so arranged as to radiate downwardly from the waist of the body *A*; but this arrangement of the springs 15 may be varied, if desired.

15 In constructing the bustle I use thinner or more elastic stays at the center or adjoining the lace-opening than I do at the outer edges, to avoid injuring the spine of the wearer, and 20 render the garment more comfortable. I do not, however, confine myself to constructing and arranging the springs in this manner, as they may be made alike or of equal rigidity at the sides and center of the bustle, if preferred.

25 It will be understood that the upper portion, *r*, of the spring *E* bends or yields when in the sheath *k*, to enable it to conform with the body of the wearer or to the shape of the 30 upper portion of the body *A*.

30 It will be obvious that the bustle may be readily detached, and the corset worn without a bustle, whenever desired; also, that the bustle, when constructed as described, 35 serves nearly all the purposes of a skirt-supporter.

Having thus explained my invention, what I claim is—

1. In a corset of the character described, the combination of the following instrumentalities, to wit: a body provided with a clasp or other suitable means for securing it to the person of the wearer, and with two or more sheaths disposed at the back of said body and opening downwardly, a bustle provided with 45 upwardly-extending springs adapted to enter said sheaths, and a cord and eyelets or other suitable means for attaching the bustle to the body of the corset, substantially as set forth.

2. In a corset of the character described, the combination of the following instrumentalities, to wit: a body provided with a clasp or other suitable means of securing it to the person of the wearer, two or more sheaths disposed at the back of said body and opening 50 downwardly, a bustle divided vertically into two sections, eyelets and a lacing-cord or other suitable means for attaching the two sections of the bustle to each other, two or more springs forming a part of the bustle and 55 adapted to enter said sheaths, and a cord and eyelets or other suitable means for attaching the bustle to the body of the corset, substantially as described.

3. The improved corset herein described, the same consisting of the body *A*, provided with the clasp *J*, sheaths *k*, eyelets *h*, lacing *f*, and eyelets *t*, and the bustle *B*, provided with the springs *E*, and eyelets *l* and the cord *v*, combined and arranged to operate as set 60 forth.

MARK A. WATERHOUSE.
